DESIGN.

No. 30,477.

J. H. THOMPSON.

Patented Apr. 4, 1899.

CHEST.

(Application filed Feb. 17, 1898.)

Fig. 1.

UNITED STATES PATENT OFFICE.

JOHN H. THOMPSON, OF KANSAS CITY, MISSOURI.

DESIGN FOR A CHEST.

SPECIFICATION forming part of Design No. 30,477, dated April 4, 1899.

Application filed February 17, 1899. Serial No. 705,895. Term of patent 14 years.

To all whom it may concern:

Be it known that I, JOHN H. THOMPSON, of Kansas City, Jackson county, Missouri, have invented a new and original Design for 5 Chests, of which the following is a full, clear, and exact description, reference being had to the accompanying drawings, forming part thereof.

My invention relates to new and useful designs for chests.

In the accompanying drawings, Figure 1 is a perspective view, and Fig. 2 is a cross-section, of the chest, showing my new design, and the leading or material features of the same 15 reside in the horizontal oblong rectangular frame 1, in the cross-piece 1^a, Fig. 2, connecting the lower edges of the oblong rectangular frame, in the longitudinal strip connecting the upper edges of the ends of said 20 frame, and in the oblong rectangular pieces parallel with cross-piece 1^a and inclosed by the said longitudinal strip and the upper edge of said frame.

Minor features of the design are embraced 25 in the chamfered enlargements of the corners of the frame, in the circular figures underlying said corners, in the hinge-like figures intersecting the strip near its ends and overlapping the oblong rectangular pieces, in the

knob-like figures projecting upward from and 30 near the outer edges of said rectangular figures, and in the handle-like figures on the sides of said elongated rectangular frame.

Referring to the drawings in detail, 1 designates the horizontal oblong rectangular 35 frame; 1^a, the cross-piece connecting the lower edges of the same; 3, the longitudinal strip connecting the upper edges of the said frame; 5, the oblong rectangular pieces parallel with cross-piece 1^a and occurring between the said 40 longitudinal strip and the upper edge of the frame; 1^b, the chamfered enlargements of the corners of the frame; 2, the circular figures underlying said corners; 4, the hinge-like figures intersecting the strip 3 and overlapping 45 the said oblong rectangular figures; 6, the knob-like figures on said oblong rectangular figures, and 7 the handle-like figures on the sides of said rectangular frame.

What I claim is—

The design for a chest, substantially as 50 herein shown and described.

In testimony whereof I affix my signature in the presence of two witnesses.

JOHN H. THOMPSON.

Witnesses:

M. R. REMLEY,
HELEN RODGERS.
